CALENDER REEL DRIVE

Elmer J. von der Heide, Akron, Ohio, assignor,
by mesne assignments, to Adamson United
Company, Akron, Ohio, a corporation of Ohio

Application March 20, 1944, Serial No. 527,314

2 Claims. (Cl. 91—48)

1

This invention relates to reel drives for rubber calenders and the like.

Rubber calenders commonly involve a vertical stack of three or more continuously driven accurately spaced parallel rolls for converting rubber stock into a continuous sheet of desired uniform thickness. The stock is ordinarily supplied to and between the upper rolls of the stack and, after passing around and back and forth between successive rolls, it passes in sheet form from the bottom rolls of the stack and onto a reel upon which it is wound.

A calender is ordinarily driven by a variable speed motor so as to permit operation at any selected speed best suited for the work at hand. Also the several rolls of the stack are ordinarily geared together to rotate at the same or at different speeds. In a three-roll calender, for instance, the motor is usually connected to drive the center roll of the stack; and two separate gear trains are provided selectively operable to drive the other rolls at the same speed as the center roll or at a lower speed. In any event, the rubber sheet issues from the calender at a rate corresponding to the peripheral speed of the bottom roll of the stack, a rate that is dependent not only upon the selected speed of the motor but also upon the selected gear train.

The calender also commonly serves to apply to or impregnate with the rubber sheet a preformed web or backing of fabric or the like by causing the latter to pass with the sheet between the bottom rolls of the stack where they combine under pressure to form a composite web. The preformed web is ordinarily received from a supply reel and the resultant composite web passes onto the receiving reel. Also, quite frequently a web of appropriate liner material from another supply reel is fed directly into the roll of material on the receiving roll to separate the convolutions thereof in a manner to prevent adhesion therebetween.

As heretofore arranged the supply and receiving reels are usually mechanically connected with the bottom roll of the stack through separate large and complicated gear trains involving friction devices which require frequent manual adjustment in order to compensate for the continuous change in the diameter of each roll of material on the reels as the operation proceeds, and to accommodate the continuous variations in reel speeds necessitated by the changing roll diameters. In spite of these adjustments the tension in each traveling web varies considerably, causing uneven winding on the receiving reel. Moreover,

the gear trains, because of their necessary size and arrangement impose an objectionable overhung load on the calender roll and also present a lubricating problem that has never been satisfactorily solved.

One object of the present invention is to eliminate the objections and difficulties above noted. This I have accomplished by providing a separate motor for each reel so controlled as to maintain the tension in the traveling web substantially constant throughout the range of variation in roll diameters.

Another object is to provide an improved and more efficient drive for the reels of calenders.

Another object is to provide in a calender a new and improved electric reel drive.

Another object is to provide a new and improved electric control system for effecting proper coordination between reel and web speeds under all conditions of operation of the calender.

Other more specific objects and advantages will appear, expressed or implied, from the following description of an illustrative embodiment of the present invention.

25 In the accompanying drawing:

Figure 1 is a schematic view diagrammatically illustrating a rubber calender equipped with a reel drive embodying the present invention.

Fig. 2 is a diagram of an electric control system employed.

The calender selected for illustration and explanation is of a type involving a vertical stack of three rolls 10, 11, and 12, which are supported in the usual manner in a conventional vertical frame not shown.

The center roll 11 is driven from a variable speed motor 13 through a pinion 14 and bull wheel 15 carried by the roll.

40 The top and bottom rolls 10 and 12 are driven from the center roll 11, either at the same speed as the latter through a train of gears 16, 17, and 18 of equal size, or at a lower speed through a separate train of gears 19, 20, and 21, the center gear 20 being smaller than gears 19 and 21. In this instance the gears 19, 20, and 21 are shown releasably connected to the rollers through appropriate means such as keys 22. When so connected the top and bottom rolls operate at speeds less than the center roll. To effect operation of all of the rolls at the same speed the keys 22 are withdrawn and transferred to the gears 16, 17, and 18 of the other train so as to render the rolls responsive to the latter.

45 A reel, here shown as a spindle 25, is arranged in front of the calender to receive and wind into

a roll 26 the web 27 as it issues from between the bottom pair of rolls 11 and 12.

A similar reel 28, supporting a supply roll 29 of fabric or other appropriate backing material, is arranged behind the calender in position to deliver the backing material in the form of a web 30 to and between the lower pair of rolls 11 and 12, by which it is pressed onto the rubber web, and from which the resulting composite web passes onto the receiving reel 25.

The two reels 25 and 28 are shown operatively connected to separate variable speed motors 31 and 32 preferably through suitable speed reduction gear units 33 and 34 respectively. The motors are connected in parallel circuits 35 and 35' both energized preferably by a single direct current electric generator 36 which is driven at a speed corresponding to the speed of the calender. The generator 36 is shown directly coupled to the main driving motor 13 so that its speed is always proportional particularly to the speed of the center roll 11.

As indicated in the diagram of Fig. 2, the generator 36 has a separately excited field 37 normally of constant strength, so that the voltage generated and transmitted to the motors 31 and 32 is proportional to the speed of the generator and consequently to the speed of the center roll 11 of the calender, and so that, unless otherwise regulated, both motors would operate at speeds proportional to that of the roll 11 and consequently proportional to the rate of travel of the web 27 when the roll 12 is geared to operate at the same speed as roll 11.

However, the rate of travel of the web 27 is determined by the speed of the bottom roll 12, so that when the latter is geared to operate at a speed lower than that of roll 11 the speed of the motors 31 and 32 should be correspondingly reduced. This is effected preferably by reducing the field strength of the generator and more particularly by introducing a resistor 38 into the field. In this instance the resistor 38 is shown connected in the field circuit with a short circuiting switch 39 connected across it so that the resistor may be rendered ineffective by closing the switch. When the bottom roll 12 is geared to operate at a speed lower than the center roll 11, the switch 39 is opened and the resistance 38 is effective to reduce the strength of the generator field, and when the roll 12 is geared to operate at the same speed as the roll 11, the switch 39 is closed to short circuit the resistance 38 and thereby increase the generator field to full strength. Whatever the conditions of operation, generator voltage is always proportional to the speed of the web 27.

It will thus be noted that by connecting the generator to the center roll 11 and by regulating its field in the manner above described, the speeds of both motors 31 and 32 are modified to compensate for changes in the rate of travel of the web 27, whether those changes result from a variation in speed of the calender as a whole or from a variation in speed between the rolls 11 and 12.

It will also be noted however that, as the web 27 wraps about the wind-up reel 25, the diameter of the roll 26 gradually increases, thereby necessitating a gradual reduction in the speed of the motor 31 and a corresponding gradual increase in motor torque in order to maintain a constant tension in the web 27. Also, as the web 30 unwraps from the supply reel 28 the diameter of the supply roll 29 gradually decreases, thereby necessitating a gradual increase in speed and reduction in

torque of the motor 32 in order to maintain a constant tension in the web 30. Provision is made for automatically regulating each of the motors 31 and 32 in such manner as to satisfy the conditions just described. Although this may be accomplished in various ways the control system shown and about to be described has proven quite satisfactory for the purpose.

In this instance each motor 31 and 32 has a 10 separately excited field 40, 40' and the control system shown includes a separate controller C or C' for each motor automatically operable to regulate the motor field in a manner to maintain armature current constant throughout the range 15 of speeds of each motor driven reel. It is, of course, understood that for any given web speed the power required to maintain a constant tension in the web is necessarily constant, and that this condition is satisfied by maintaining armature current constant, because, as above noted, the motor voltage derived from the generator 36 is constant for any given web speed. This is true even though motor speed varies with variations in reel speeds, because such speed variations are 20 accompanied by proportionate but inverse variations in motor torque.

The two motor controllers shown are identical. Each includes a pair of thyratron tubes 41 through which the motor field is excited, the tubes being arranged to respond to fluctuations 30 in current in the motor circuit 35 or 35' and to so modify the motor field strength as to maintain the current constant. The tubes of each controller are energized from any appropriate alternating current source through a circuit 42 and transformer 43.

Each thyratron tube 41 contains the usual heater filament 44 energized from a secondary winding 45 of the transformer 43 through a circuit 46, and the anodes 47 of each pair of tubes are connected preferably through protective resistors 48 to opposite ends of a second secondary winding 49 of the transformer 43 from which they are energized. Each pair of tubes also contain the usual cathodes 50 which are both connected through one side of the circuit 46 to and through a variable resistor 51 to one side 52 of the motor field circuit 40 or 40' to excite the latter. In this instance side 52 of the field circuit is connected to the moveable contact 53 of the resistor 51 and contains a second variable resistor 54 by which the field strength may be manually regulated. The other side 55 of each motor field circuit is connected to the winding 49 at a midpoint thereof. The field 40 and 40' of each motor is thus energized from one of the windings 49 through the pair of thyratron tubes connected therewith.

The flow of electrical energy through the tubes however is regulated by regulating the potential 60 on the grids 56. In this instance, the grids are energized from a third secondary winding 57 of the transformer 43 through means arranged to maintain the required out-of-phase relation between the grid and anode potentials. The means shown for this purpose includes a resistor 59 and a variable inductance 60 respectively connected to the opposite ends of the winding 57 and both connected to one end of a primary winding of a second transformer 61, the other end of which is connected to the winding 57 at a mid point. The grids of each pair of tubes are connected to opposite ends respectively of the secondary winding 62 of the transformer 61 through the usual resistor 63. A capacitor 64 connected across the grid 56 and cathode 50 of each tube serves to

smooth out the pulsations in current flowing through the latter.

Grid regulation is effected through a control circuit between the grid and cathode of each tube and including resistors 69 and 65 connected in series with each other and with and between the variable resistor 51 and the winding 62 at a mid point of the latter. This control circuit is rendered responsive to variations in current in the associated motor circuit 35 or 35', and for this purpose the resistor 65 is connected across the commutating field 66 or 66' of the associated motor through leads 67 and 68, so that any variation in the voltage drop across the commutating field 66 or 66', resulting from a variation in current flow in the motor circuit 35 or 35', causes an advance or retardation in the firing point of the grids 56 of the connected pair of tubes to thereby increase or decrease the current flow through the field 40 or 40' of the connected motor.

Either controller may be adjusted to best suit any of various operating conditions and to maintain the armature current of each motor at any desired value.

For example, the controller C for the wind-up motor 31 may be adjusted, by adjusting the resistor 51, to provide excitation of the motor field 40 corresponding to a speed above the weak field speed of the motor, so that the motor tends to drive the receiving reel 25 at a speed greater than the calender roll. Then, when the first wrap of the web 27 is taken by the reel 25, any slack in the web is rapidly taken up and tension is established. Thereupon, the armature current immediately increases as a result of the reduction in motor speed, and the controller immediately functions to increase the field strength and thereby establish the armature current at the desired value, this value being determined not only by the setting of the resistor 51 but also by manual adjustment of the resistor 54.

Thereafter, as the roll 28 on the reel 25 builds up, the armature current tends to increase as the motor speed decreases, but to each increment of increase in current the controller responds by increasing the field strength and thus restoring the current to the value for which the controller has been set. Consequently, although the speed of the motor gradually decreases, the armature current is held constant and the field strength gradually increases until full field or base speed is established, the base speed corresponding to the speed of the reel at maximum roll diameter.

The controller C' for the unwind motor 32 is adjusted in a similar manner to provide an initial field strength greater than full field at base speed, so that the motor 32 tends to operate in the same direction as motor 31 but at a speed such that the speed of the supply roll 29 is less than that of the calender rolls. Consequently, when the web 30 is threaded into the calender, any slack therein is rapidly taken up by the calender until tension in the web is established. Thereupon, the speed of the motor 32 increases and thereafter the motor functions as a braking generator returning electrical energy to the system through the circuit 35'. The controller C' functions in substantially the same manner as the controller C to maintain the generated current substantially constant by decreasing the field strength as the speed of the braking generator (motor 32) increases. That is to say, as the size of the roll 29 gradually decreases with a resultant increase in braking generator speed, the arma-

ture current tends to increase, but the controller responds by progressively decreasing the field strength, and thereby maintaining constant current, until maximum speed at weak field is established, a speed that corresponds to the speed of the supply reel at minimum roll diameter.

It will thus be noted that, controlled in the manner above described, both motors 31 and 32 will operate at the varying speeds and torques necessary to maintain a constant tension in both webs 27 and 30 at a given calender speed, and that this condition prevails at all speeds of operation of the calender since the voltage developed by the generator 36 and transmitted to both motors is always proportional to the rate of operation of the calender.

Moreover, this condition maintains whether the calender is adjusted to effect operation of the bottom roll 12 at the same speed as the center roll 11 or at a lower speed. Whenever the bottom roll 12 is operating at the lower speed, the switch 39 is opened so that the resistor 38 is effective to reduce the strength of the generator field 37 and thereby reduce the voltage to a value corresponding to the lower web speed resulting from the reduced speed of the bottom roll 12; and whenever the bottom roll 12 is operating at the same speed as the center roll 11, the switch 39 is closed to short circuit the resistor 38 and thereby restore the generator field 37 to full strength so that the generated voltage is increased to a value corresponding to the higher web speed.

It will be further noted that with the motors 31 and 32 thus separately controlled in a manner to maintain the armature current in each circuit 35 and 35' substantially constant, the current thus maintained constitutes a measure of the tension maintained in each web 27 and 30. This is readily demonstrated. The power required to maintain a given tension in either web is the product of web speed times web tension, and the power supplied by each motor for maintaining that tension is equal to the product of the voltage and current maintained in each motor circuit, and since, as above pointed out, the voltage in both circuits 35 and 35' is the same for any given web speed, it necessarily follows that the current maintained in each circuit 35 and 35' is proportional to the tension in the corresponding web. Therefore, an ammeter placed in either circuit 35 or 35' will provide an accurate visible indication of the tension in the web 27 or 30, respectively, and constitute a useful guide in regulating the tension in either web which may be readily accomplished by appropriate manual adjustment of one or the other of the variable resistors 54.

A reversing switch 70 is preferably included in the field circuit 52-55 of each motor 31 and 32 to permit reversal of either motor at will.

Various changes may be made in the embodiment of the invention hereinabove specifically described without departing from or sacrificing the advantages of the invention as defined in the appended claims.

I claim:

1. The combination of a calender having a stack of rolls coating to form and apply a sheet of rubber or the like to a web, means for supplying the web thereto, a reel for receiving the combined web and sheet formed by said rolls, means including a motor for driving said rolls, said means also including means adjustable to vary the speed ratio between said rolls with a con-

sequent variation in the rate of discharge of said combined web and sheet from said rolls, a second motor for driving said reel, a generator driven by said first named motor for normally maintaining the armature voltage of said second motor proportional to the speed of said first named motor, means for varying the field strength of said generator to thereby modify said voltage in accordance with the variation in speed ratio between said rolls, and an electronic controller responsive to the armature current of said second motor for maintaining said armature current substantially constant throughout the speed range of said reel.

2. The combination of a calender having a stack of rolls coacting to form and apply a sheet

of rubber or the like to a web, means for supplying the web thereto, a reel for receiving the combined web and sheet formed by said rolls, a motor for driving said reel at varying speeds to compensate for variations in diameter of the roll of material thereon, means adjustable to vary the speed ratio between said rolls with a consequent variation in the rate of discharge of said combined web and sheet from said rolls, means for maintaining the armature voltage of said motor substantially proportional to said rate of discharge of said combined web and sheet, and an electronic controller responsive to the armature current of said motor for maintaining said current substantially constant.

ELMER J. VON DER HEIDE.
